UNITED STATES PATENT OFFICE

1,979,216

HEAT TREATMENT CHAMBER

William A. Morton, Pittsburgh, and Paul L. Geer,
Bellevue Borough, Pa., assignors to Amco, Incorporated, Pittsburgh, Pa., a corporation of Pennsylvania

Original application February 25, 1923, Serial No. 256,856. Divided and this application October 17, 1931, Serial No. 569,432

18 Claims. (Cl. 49—47)

This application is a division of our patent application Serial Number 256,856, filed February 25, 1928.

One of the objects which we have in view is the provision of means whereby the articles to be treated may be introduced into the heat-treatment chamber in single file or as received and then distributed for substantially the full internal width of the chamber. We are thus enabled to utilize the full capacity of the chamber.

For this purpose we provide an intake conveyer of less cross-sectional area but traveling at greater speed than the conveyer to which it delivers the articles, together with means for transferring the articles from the intake conveyer to the receiving conveyer and distributing the articles over the entire effective width of the chamber.

We are also enabled to provide a relatively narrow intake opening in the front of the chamber, thus eliminating a very substantial heat loss.

Another object which we have in view is the maintenance of heat uniformity in the articles during the heat-treatment operation, and we accomplish this by delivering the article by means of a relatively high speed intake conveyer to a more slowly moving chamber conveyer, thus causing the articles to be arranged in juxtaposition.

Other novel features of design and construction, and also of the arrangement of parts will appear from the following description.

In the accompanying drawings wherein we have illustrated a practical embodiment of the principles of our invention in connection with a lehr for annealing glassware, Fig. 1 is a vertical section of the lehr taken along the line 1—1 in Fig. 2; Fig. 2 a horizontal section taken along the line 2—2 in Fig. 1; Fig. 3 an enlarged broken view partially in elevation and partially in section of the front conveyer shaft within the lehr and certain of the sprockets thereon; Fig. 4 an enlarged detail showing two of the conveyer shafts and their associated parts, and Fig. 5 a diagrammatic view illustrating the drive.

Referring to the drawings, the lehr tunnel or chamber is built of suitable material which is non-conductive of heat, and comprises the base 1, the side walls 2 and the roof 3. The rear or discharge end of the tunnel is preferably open for its full width to permit the extension of the conveyer therethrough, but the front or intake end of the tunnel is closed except for a relatively narrow central opening 4 through which the intake conveyer extends.

Instead of the usual single endless conveyer ex-

tending through the full length of the lehr tunnel, in our improved lehr we employ a plurality of sets of endless conveyers which may be belts or chains and whose ends are so associated that the articles travel from one to the next. The number of such sets may be determined by the length of the lehr tunnel or chamber and each conveyer or set of conveyers is short enough to substantially localize the zones of heat transference so as to minimize such loss.

As a suitable form of conveyer for the purposes of my improved lehr, we have invented a conveyer comprising a plurality of sets of endless conveying chains, the members composing the sets being in parallelism and carried at their ends on axially aligned sprockets, and the sprockets for the adjacent ends of two sets being alternately arranged on a common shaft.

Thus 5a, 5b, 5c and 5d represent four sets of parallel conveying chains, having their ends carried on sprockets designated generally by the numeral 6, and at the adjacent ends of said sets the sprockets which carry the chains of one set are alternately arranged on a shaft with the sprockets of the other set, so that the chains of adjacent sets are interlaced at their ends and thus form in effect a continuous interlocked conveying surface.

The sprockets carrying the rear end of the rear or discharge conveyer comprising the chains 5a are fast on a shaft 7 which is journaled in bearings 8 beyond the discharge end of the tunnel, and said shaft is rotated at proper speed in a direction which is clockwise in Fig. 1. Thus the end of said shaft is provided with a driving sprocket 9 connected by a chain 10 to a speed reducer 11 which in turn is connected by a chain 12 with a variable speed transmission mechanism 13 which in turn is driven by a motor 14.

15, 16, 17 and 18 represent shafts disposed transversely of the chamber or lehr tunnel and having their ends journaled in the side walls thereof, the ends of the shafts protruding at one side of the chamber for mounting driving sprockets thereon.

The protruding end of the shaft 15 is provided with a large sprocket 19 which is connected by a chain 20 with a like sprocket 21 on the shaft 7, thus driving shafts 7 and 15 in unison, and preferably at the same speed. The shaft 15 is provided with a second and smaller sprocket 22 which is connected by a chain 23 with a larger sprocket 24 on the shaft 16. The shaft 16 is further provided with a smaller sprocket 25 which

is connected by a chain 26 with a larger sprocket 27 on the shaft 17.

It is thus apparent that the shafts 15, 16 and 17 are driven from the shaft 7 but at progressively lessened speed.

The shaft 17 is further provided with a smaller sprocket 28 which is connected by a chain 29 with a sprocket 30 of a variable speed transmission device 31 which in turn is coupled to the 10 protruding end of the shaft 18.

The shaft 18 is driven at a greater speed than the shaft 17 for a purpose to be more fully described, and its relative speed may be regulated.

The sprockets which carry the front ends of 15 the conveyer chains 5a are loose on the shaft 15, while the sprockets which carry the rear ends of the chains 5b are fast on the shaft 15. The sprockets which carry the front ends of the chains 5b are loose on the shaft 16 while the 20 sprockets which carry the rear ends of the chains 5c are fast on the shaft 16. The sprockets which carry the front ends of the chains 5c are loose on the shaft 17 while the sprockets which carry the rear ends of the chains 5d are fast on the 25 shaft 17. The sprockets which carry the front ends of the chains 5d, indicated at 6a in Fig. 3 are loose on the shaft 18 and alternating on shaft 18 between the sprockets 6a on the central portion of shaft 18 are the sprockets 6b which are 30 fast on the shaft 18 and which carry the rear or inner ends of the chains 5e which form the intake conveyer and which extend forwardly through the front opening 4. At their front ends the chains 5e are carried by sprockets 6c which 35 are carried by a shaft 32 whose ends are journaled in a stand 33 mounted on and vertically adjustable relatively to a base 34.

Within the front end of the lehr tunnel and at either side of the intake conveyer a horizontal transfer table 35 is mounted, and suitable means are provided for transferring the ware from the intake conveyer across said table to the conveyer chains 5d.

Thus we may provide an oscillating sweeper 45 arm 36 fixed to the lower end of a vertical shaft 37 depending through the roof of the tunnel and journaled in a suitable stand 38 mounted on the roof. The upper end of the shaft 37 is provided with a beveled pinion 39 which is engaged by two 50 oppositely arranged, interrupted beveled pinions 40 fast on a horizontal shaft 41 which is driven in a constant direction as by a motor 42. The arm 36 is thus caused to swing alternately in opposite directions over the intake conveyer, the 55 transfer tables and the front ends of the conveyer chains 5d.

The side surfaces of the arm 36 are conformed to properly engage the ware. Thus they may be provided with recesses 43 to fit the sides of the 60 ware, an arm with properly shaped recesses being substituted to suit the particular ware to be introduced into the lehr. The tables 35 are provided with arcuate guides 44 to assist in maintaining the ware in proper paths while being 65 transferred.

We provide means for supplying the necessary heat to the front portion of the lehr for the annealing operation.

Thus 45 represents a combustion chamber extending under the front of the lehr tunnel, a removable metal plate 46 forming the roof of the chamber and the floor of the tunnel and said plate being apertured as at 47 for the admission of heat to the tunnel. 48 is a gas burner extending into the front end of the chamber 45. A

flue 49 extends rearwardly from the chamber 36 under the tunnel, the roof-floor being formed by the removable plates 50. At its outer end the flue 49 is connected to an exhauster 51 coupled up to the variable speed transmission mechanism 13.

52 represents metal boxes which forms the roof of the rear or discharge end of the tunnel and have perforated floors. Each of said boxes is connected by a pipe 53, provided with a valve 54 with a header pipe 55 which is connected to a blower 56 driven by a chain 57 leading to the speed reducer 11. Thus air may be introduced into the tunnel for the proper reduction of the temperature, such introduction being controlled and graduated by means of the valves 54.

It is evident that by properly proportioning the relative speeds of the chains of the intake conveyer and of the chains of the lehr conveyers and employing the transfer device for receiving the intaken article and depositing it on the lehr conveyers, the full capacity of the lehr may be utilized and the output of the same may be greatly increased without increasing the length of the lehr. This works a decided economy of valuable 100 factory space and also an economy in fuel consumption.

It is further evident that the aggregate temperature loss attending the operation of the lehr is greatly reduced and consequently the amount 105 of heat replacement required is correspondingly lessened.

It is further evident that owing to the relatively fast speed of the intake conveyer compared to that of the chains 5d the articles will be arranged in close juxtaposition on the chains 5d and will thus be maintained at substantially uniform temperature while traveling on said chains. The arrangement whereby the chains progressively increase in speed of travel toward the rear 115 or discharge end of the chamber results in the gradual separation of the articles as they approach the discharge or cooling end of the chamber, thus facilitating the cooling of the articles.

What we desire to claim is:—

1. In an article heat treating furnace and loader combination, the arrangement which comprises a lehr tunnel, a conveyer for passing articles therethrough, a loader conveyer entering the open end of said tunnel in overlapping relation 125 with the first named conveyer, means for operating the said last named conveyer at a greater delivery speed than the speed of the said first named conveyer and means for periodically moving the articles laterally from the loader conveyer to deposit them upon the first named conveyer.

2. In an article heat treating furnace and loader combination, the arrangement which comprises a lehr tunnel, an endless conveyer for passing 135 articles therethrough, an endless loader conveyer entering the open end of said tunnel and travelling in a fixed path, the inner end of the loader conveyer turning about the same axis as the adjacent end of the first named conveyer, means 140 for operating the conveyers at relatively different speeds and means for periodically moving the articles laterally from the loader conveyer to deposit them upon the first named conveyer.

3. In an article heat treating furnace and loader combination, the arrangement which comprises a tunnel, a conveyer for passing the articles through said tunnel, a loader conveyer delivering the articles to the tunnel, the inner end 145 of the loader conveyer and the receiving end of 150

- the first-named conveyer being in overlapping relation for periodically removing articles from the intake, and an arm oscillating between the said intake conveyer and depositing them on said conveyers to transfer the articles laterally from one conveyer means to another conveyer means, said means depositing said articles on the loader conveyer to the tunnel conveyer alternately on either side of the center of said 80
5. 4. In an article heat treating furnace and loader conveyer means, the combination of a tunnel, a conveyer for passing the articles through said tunnel, a loader conveyer depositing articles to travel through the tunnel, an intake conveyer for delivering the articles to the tunnel, an arm oscillating into the front end of the tunnel, a chamber of narrower effective cross-sectional capacity and traveling at greater speed than said loader conveyer, and means for alternately 85
10. 5. The combination of a heat-treatment chamber conveyers being in overlapping relation, and a loader conveyer means arranged to cause the articles to travel through the chamber, an intake conveyer periodically removing the articles from the intake, extending into the front end of the chamber of intake conveyer and depositing them in spaced narrower effective cross-sectional capacity and in relation across the conveyer means. 90
15. 6. The combination of a heat-treatment chamber conveyer means arranged to cause the articles to travel through the chamber, an intake conveyer periodically removing the articles from the intake, extending into the front end of the chamber of intake conveyer and depositing them in spaced narrower effective cross-sectional capacity and in relation across the conveyer means. 95
20. 7. In a combined article heat-treating furnace and loader structure, the combination of a tunnel, a high speed loader conveyer extending into the receiving end of the tunnel for the introduction of the articles to be heat-treated, said loader conveyer being arranged to travel in a fixed path, the adjacent ends of the two 100
25. 8. The combination of the articles laterally from the intake conveyer, the loader conveyer being arranged to travel in a fixed path, a low speed main conveyer for conducting the articles through the tunnel, and means for transferring the articles from the loader conveyer to the main conveyer, said means comprising an oscillating arm arranged to swing over the surface of the loader conveyer and in opposite directions to alternately move articles to either side from the loader conveyer and alternately arrange them in rows on the main conveyer. 105
30. 9. The adjacent ends of the two conveyers being in overlapping relation, and means for removing articles longitudinally aligned on the intake conveyer and depositing them on said conveyer means in transverse alignment thereon. 110
35. 10. 7. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and a swinging transfer device arranged to remove the articles from the intake conveyer and deposit them on said conveyer means. 115
40. 8. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 120
45. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 125
50. 10. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 130
55. 11. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 135
60. 12. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 140
65. 13. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 145
70. 14. 9. The combination of a heat-treatment chamber, conveyer means arranged to cause the articles to travel through the chamber, an intake conveyer extending into the front end of the chamber of narrower effective cross-sectional capacity and traveling at greater speed than said conveyer means and aligned therewith, said intake conveyer being arranged to travel in a fixed path, the adjacent ends of the two conveyers being in overlapping relation, and means for periodically removing the articles from the intake conveyer and depositing them on said conveyer means. 150

travel in a fixed path and the ends of the chains of the delivery conveyer interlacing with the adjacent ends of the chains of the main conveyer, means arranged to swing over the delivery conveyer to sweep the articles laterally off the delivery conveyer and to arrange said articles in rows on and transversely of the main conveyer, and means for causing the delivery conveyer to travel at a higher linear speed than the main conveyer.

15. In a tunnel lehr for annealing glassware, the combination of a tunnel, a main conveyer within the tunnel and comprising a plurality of endless chains arranged in parallelism, a ware-delivery conveyer extending into the intake end of the tunnel and also comprising a plurality of endless chains arranged in parallelism, and means comprising a member swinging on a substantially vertical axis and moving over the surface 20 of the delivery conveyer and arranged to sweep articles laterally from the delivery conveyer and arrange said articles on the main conveyer in rows disposed transversely thereof.

16. In a tunnel lehr for annealing glassware, 25 the combination of a tunnel, a main conveyer within the tunnel and comprising a plurality of endless chains arranged in parallelism, a ware-delivery conveyer extending into the intake end of the tunnel and also comprising a plurality of endless chains arranged in parallelism, and means comprising a member swinging on a substantially 30 vertical axis and moving alternately in opposite directions over the surface of the delivery con-

veyer and arranged to sweep articles laterally from the delivery conveyer and arrange said articles on the main conveyer in rows disposed transversely thereof.

17. In a tunnel lehr for annealing glassware, 80 the combination of a tunnel, a main conveyer for causing the glassware to travel through said tunnel, a loader conveyer extending into said tunnel and axially aligned with the first named conveyer, and a transfer device mounted to swing on a substantially vertical axis over the loader conveyer and arranged by alternate movements to sweep the articles first in one direction and then in the other direction from the loader conveyer and to arrange them in rows on and transversely of the first named conveyer.

18. In a tunnel lehr for annealing glassware, 85 the combination of a tunnel, a main conveyer for causing the glassware to travel through said tunnel, a loader conveyer extending into said tunnel and axially aligned with the first named conveyer, and a transfer device mounted to swing on a substantially vertical axis over the loader conveyer and arranged by alternate movements to sweep the articles first in one direction and then 90 in the other direction from the loader conveyer and to arrange them in rows on and transversely of the first named conveyer, the loader conveyer moving at a greater speed than the first named conveyer.
